UNITED STATES PATENT OFFICE.

WILBUR F. SANDERS, OF CHICAGO, ILLINOIS.

DESK PAD.

Application filed December 29, 1928. Serial No. 329,129.

My invention relates to desk pads. It relates more particularly to a desk pad of novel character adapted to take the place of the usual large desk blotter.

5 The use of a table top directly for writing purposes is usually found so undesirable that practically all desks are at the present time equipped with a large blotter, supported at the corners and bottom by a specially designed back, leaving the blotter to be used as a writing surface. It is presumed that this blotter will be changed very frequently, but it is common knowledge that in actual practice it cannot be changed frequently enough to maintain a clean tidy appearance at all times. Moreover the blotter does not offer an entirely satisfactory writing surface for both pen and pencil.

Accordingly the principal object of my 20 present invention is the provision of an improved desk pad to take the place of the blotter described.

Another object is the provision of a desk pad which will always look neat and clean, 25 and which forms a very satisfactory writing surface for both pen and pencil.

Another object is to produce a writing pad on which paper will not slip.

Another object is to provide a writing pad 30 which will lie flat on the desk at all times and which will not slide with respect to the desk.

Another object is the provision of a writing pad which will not be injured or marked by lighted cigars or cigarettes, when coming 35 in contact therewith.

Another object is the provision of a writing pad which may be finished in a number of artistic designs and color combinations so as to be a real ornament to a desk.

40 Other objects and features of the invention will be apparent from a consideration of the detailed description taken with the accompanying drawings wherein—

Fig. 1 is a fragmentary perspective view of 45 a desk showing my improved writing pad on the top thereof, and

Fig. 2 is a fragmentary enlarged sectional view taken along the line 2—2 of Fig. 1.

The pad of my invention is adapted to be 50 applied to an ordinary table top 11 and comprising a middle writing surface 12 with raised side edges 13 and 14. The raised edges are ornamented in suitable design, and also act to prevent pencils and the like from rolling 55 ing off the pad. The middle portion of the

desk pad is perfectly flat and is designed to offer the very best possible writing surface.

Possibly my pad could be produced from a number of combination substances, but I have been able to get unusually good results by the 60 use of a suitably filled vulcanized rubber compound properly processed and treated to bring out the characteristics desired. The real basis of the composition is rubber and clay, a comparatively large proportion of the 65 rubber being reclaimed and so acting somewhat as a filler, the principal binding depending mostly upon the new rubber. I believe that the clay being refractory has a great deal to do with the unburning characteristics of the pad, 70 and I know that it has its effect upon the degree of hardness which is of course controlled as it has a great deal to do with the writing quality of the pad. While I am not necessarily restricted to any particular combination 75 of substances I shall disclose one particular formula with which I have obtained unusually good results. This consists of standard crepe sheets 6 parts, white reclaimed rubber 17 parts, gray reclaimed rubber 14 parts, 80 lithopone 4 parts, sulphur 1 to 4 parts depending upon the accelerator etc., a suitable organic accelerator, oil and resin about 1 part each, 27 parts of clay, and approximately 8 parts of whiting. Coloring material is added 85 depending upon the finish desired and for example when producing a green pad I use 8 parts of chrome green.

In making the pad I mix the various ingredients in the usual way and cure the pad 90 in a heated mold as is done with rubber products. The specific manner of carrying out the steps of the process of course may be made to vary.

The drawing is shaded to show a mottled 95 effect, and this is the design which I find most advantageous. In color combinations I have employed green, blue, brown, etc. with a mottled white mixture, as well as combinations of more than one color with white. 100 For example a mottled pad consisting of dark brown, tan and white has been produced with unusually good results, as well as mixtures of a dark gray, blue and white. When formed in this way the pad does not 105 follow any orderly design, but of course it can be made in an orderly design should anything of this sort be desired.

A pad made in accordance with my invention is extremely neat and convenient, and 110

provides an unsurpassed writing surface for either pen or pencil. A single sheet of paper may be laid on the pad, and without holding the sheet with the hands at all the paper 5 may be written on and it will hold its position due entirely to its contact with the pad. It will not stick to the pad, however, and if it is desired to move any papers around on the pad they can be moved around freely 10 without any possibility whatsoever of causing any adhesion. The pad can be washed off with a damp cloth and so can be spotlessly clean at all times. A lighted cigarette may be laid on the pad and allowed to burn 15 its entire length, and although there will be a slight discoloration due probably to the nicotine present in the cigarette, this spot can be washed off and no permanent discoloration of the pad results. Ink spots absolutely 20 will not penetrate it, and although they of course leave their mark, they can be washed off with clear water. The desk pad is extremely more economical than blotters and is an improvement in every essential respect. Although I have described specific 25 features of my invention including details of composition to enable those skilled in the art to practice the same it is obvious that I do not intend to restrict myself except in so far as defined by the appended claims.

What I claim as new and desire to protect by Letters Patent of the United States is:

1. As a new article of manufacture a desk pad formed of a material having a rubber 35 base and suitable fillers and adapted to lie flat on the desk without sliding and having such a degree of hardness that the top sur-

face serves as a proper writing surface when employing only a single thickness of paper and when writing with either pen or pencil. 40

2. As a new article of manufacture a desk pad of proper dimensions to be supported on a desk for a writing pad, and formed of molding compound including rubber of such a degree of noncombustibility as not to be 45 permanently marked by contact with a burning cigar or cigarette.

3. As a new article of manufacture a desk pad formed of molding material having a rubber base of suitable dimensions to be supported on a desk, and with its top surface provided with such a finish as will support a single sheet of paper without slipping when writing thereon, and when the only contact with the paper is with the writing 55 instrument itself.

4. As a new article of manufacture a desk pad of suitable shape to be supported by the desk, and formed of a molding compound including rubber and a refractory material. 60

5. As a new article of manufacture a desk pad of suitable shape to be supported by the desk, and formed of a molding compound including rubber and clay.

6. As a new article of manufacture a desk 65 pad of suitable shape to be supported on a desk and formed of a molding compound including raw rubber, reclaimed rubber, sulphur coloring matter, a white filler, clay, oil and rosin.

In witness whereof, I hereunto subscribe my name this 10th day of December, 1928.

WILBUR F. SANDERS.
